[57] CLAIM

The ornamental design for a cord storage and prong protector device, as shown and described.

DESCRIPTION

FIG. 1 is a side view of a device showing my new design in solid lines connected to an electrical adaptor including a cord and plug as shown in broken lines;

FIG. 2 is a side view showing the device in solid lines disconnected from the adaptor shown in broken lines;

FIG. 3 is a top view of the device;

FIG. 4 is a bottom view thereof;

FIG. 5 is a front view thereof, the left side view being identical;

FIG. 6 is a right side view thereof; and,

FIG. 7 is a rear view thereof.

The broken line showing in FIGS. 1 and 2 is included for the purpose of illustrating environmental structure only and forms no part of the claimed design.
